FREQUENCY MODULATION OF ELECTRON
DISCHARGE DEVICESLloyd P. Smith, Ithaca, N. Y., assignor to Radio
Corporation of America, a corporation of Dela-
ware

Application February 14, 1948, Serial No. 8,332

8 Claims. (Cl. 332—5)

1

2

My invention relates particularly to frequency modulation of magnetrons and similar electron discharge devices. However, the principle involved may be applied to frequency variation of cavity resonators in general or to varying the capacity between any spaced conductive elements.

The principal object of my invention is to provide a novel method and apparatus for modulating the generated frequency of a magnetron in accordance with a given signal.

Another object of my invention is to provide a novel method and apparatus for varying the capacitance between two or more spaced conductive elements.

Another object of my invention is to provide an improved method and apparatus for varying the resonant frequency of a cavity resonator.

These and other objects will appear hereinafter.

The novel features of my invention are set forth with particularity in the appended claims, but the invention itself will be best understood by reference to the following description taken in connection with the accompanying drawing, in which:

Figure 1 is a perspective view partly cut away of a vane type multi-cavity magnetron illustrating one embodiment of my invention;

Figure 2 is a top plan view partly in section of the magnetron shown in Figure 1;

Figure 3 is a perspective view similar to Figure 1 of a pole type magnetron illustrating another embodiment;

Figure 4 is a top plan view in section on the line IV—IV of Figure 5 of a cavity type magnetron illustrating the application of my invention to two cavities; and

Figure 5 is a section view taken on the line V—V of Figure 4.

The capacitance between certain spaced elements can be varied by properly moving a conductor relative to said elements. This is conveniently done, in accordance with my invention, by movably mounting the conductor adjacent said elements, providing a constant magnetic field at right angles to the conductor and passing a current thru the conductor, which results in a force on the conductor at right angles to both current and field, thereby causing motion of the conductor in the direction of the force and a consequent change in capacitance between said elements.

In frequency modulation it is the object to effect a change in the generated frequency ac-

cording to some desired function of the time. By passing an alternating current corresponding to a given signal or other intelligence thru said conductor the resonant frequency of the device with which said elements are associated is modulated according to said intelligence.

Referring to Figures 1 and 2 of the drawing, the vane type cavity magnetron disclosed therein comprises a cylindrical envelope wall 1 having integral vanes 2 constituting anode segments and forming a cavity resonator therebetween. Although only two vanes forming a single cavity resonator are illustrated, it will be understood that the complete magnetron will have an even number of vanes 2 equally distributed around the envelope wall 1, and that a change in the frequency of one resonator will change all the resonators. The inner edges of the vanes 2 are spaced from the center of the structure to define a cylindrical cathode space, and a cathode C is supported by any suitable means in said space. The usual magnetic field parallel to the cathode and normal to the path of electrons between the cathode and anode is produced by a permanent magnet M, Figure 5, or other suitable means. A pair of end plates 3 complete the vacuum envelope. It will be understood that the anode structure 1, 2 and cathode C will be maintained at such potential difference relative to the magnetic field strength as to produce the usual spoke-like rotating space charge in the cathode space and the oscillating electric fields in the cavity resonators.

The conventional magnetron as described in the preceding paragraph can oscillate in one or more of several different modes, but is, by strapping alternate vanes together or by other means made to oscillate in the so-called π -mode wherein adjacent cavity resonators oscillate 180° out of phase at a definite frequency which is determined largely by the form and dimensions of each cavity resonator. This frequency can be varied, within certain limits, by increasing or decreasing the capacitance between the adjacent inner portions of the vanes forming the side walls of the cavity resonators.

In accordance with my invention, each of the vanes 2 is provided at its inner end with a post 4 extending outwardly therefrom in a direction parallel with the cathode C and the magnetic field. A conductive member such as metal bar 5 is movably mounted relative to two adjacent posts 4, in the space between the cover plate 3 and the ends of the vanes 2, by means of a flexible metallic strip of which one end is attached

at 7 to the envelope wall 1 and the other end is passed through an insulating seal 8 in an aperture 9 of the wall 1. The distance between the bar 5 and the ends of the vanes 2 is large compared to the normal spacing between the bar 5 and the posts 4, to minimize the capacitance between the former. The ends of the bar 5 are electrically connected through the strip 6, wall 1, conductors 11 and control resistor 12 to a source of alternating current 10 in accordance with which it is desired to modulate the magnetron oscillations.

In operation, the current from source 10 passing through the bar 7 at right angles to the magnetic field produces a force on the bar at right angles to the current and field, that is, toward or away from the posts 4, depending on the instantaneous direction of the current in the strip, and the resulting motion of the bar 7 changes the capacitance between the posts 4 and consequently the resonant frequency of the cavity resonator.

Figure 3 illustrates the application of my invention to a pole type magnetron having a single cavity resonator formed by a cylindrical wall 21 and end plates 22. The anode vanes of Figures 1 and 2 are replaced in this form of magnetron by an annular series of parallel anode rods or poles 23 defining a central cathode space. For convenience only two poles have been shown. The structure for varying the capacitance between the poles 23 comprises a bar 25 movably mounted relative to the two adjacent poles shown by means of a flexible metallic strip 26 attached to the wall 21 at 27 and sealed through an insulator 28 in aperture 29, as shown, and connected by conductors 31 and control resistor 32 with the modulating source 30. The operation of this embodiment of the invention is similar to that described above for Figures 1 and 2, the variation in capacitance between adjacent poles 23 resulting in a corresponding modulation of the generated frequency of the magnetron.

In Figures 1 to 3, the invention has been applied to changing the capacitance between two magnetron elements only. However, it can be applied to as many elements as desired. In Figures 4 and 5, I have shown the manner in which two adjacent cavity resonators may be effectively tuned simultaneously. The envelope 41, vanes 42, cathode C, end plates 43, posts 44, bar 45, strip 46, and insulator 48 are similar to the corresponding elements in Figures 1 and 2. In this form, however, the upstanding posts 44 are circular in cross section and the capacitance bar 45 is provided with an arcuate recess facing each post, in order that the rectilinear motion of the bar 45 will produce equal changes in the capacitances between adjacent posts. Obviously, the bar 45 may be extended to cooperate with all of the vane posts on one side of a diametral plane, and another bar may be similarly arranged on the opposite half of the vane structure and connected in series with the first bar and the alternating current source, in order to vary directly the resonant frequency of all of the cavity resonators.

The invention has been illustrated specifically as applied to a magnetron type of electron discharge device, being particularly useful therein because the existing magnetic field of the magnetron also cooperates with the modulating current to produce the desired vibratory movement of the capacitance bar. However, the invention can be applied equally well to any cavity resonator or other device with which one is prepared to

use a magnetic field. Various modifications may be made without departing from the scope and spirit of the invention as defined in the appended claims.

5. What is claimed is:

1. A cavity resonator including a plurality of spaced conductive elements, and means for varying the resonant frequency of said resonator, by varying the capacitance between said elements, 10 comprising an elongated conductive member movably mounted adjacent said elements and means for vibrating said member relatively to said elements, said vibrating means including means for establishing a constant magnetic field substantially normal to said conductive member and means connecting said conductive member in series with a source of modulating current.

2. An electron discharge device including a plurality of spaced conductive elements, and means for varying the frequency of said device, by varying the capacitance between said elements, comprising an elongated conductive member movably mounted adjacent said elements and means for vibrating said member toward and away from said elements, said vibrating means including means for establishing a constant magnetic field substantially normal to said conductive member and means connecting said conductive member in series with a source of modulating current.

3. A magnetron including an annular series of parallel anode elements, an elongated cathode positioned axially of said anode elements, means for establishing a constant magnetic field substantially parallel to said anode elements and said cathode, and means for modulating the generated frequency of said magnetron, by varying the capacitance between said anode elements, comprising an elongated conductive member movably mounted near two adjacent anode elements and 40 lying in a plane substantially normal to said anode elements, and means extending from the ends of said conductive member connecting the latter in series with a source of modulating current, whereby said member is vibrated toward and 45 away from said two anode elements when said magnetic field is established and a modulating current is passed through said member during operation of said magnetron.

4. A vane type magnetron including a cavity resonator partially bounded by two spaced anode vanes, and means for varying the resonant frequency of said resonator comprising an elongated conductive member movably mounted adjacent said vanes and means for vibrating said member toward and away from said vanes, said vibrating means including means for establishing a constant magnetic field substantially normal to said member and means connecting said member in series with a source of modulating current.

5. A magnetron in accordance with claim 4, wherein each of said vanes is provided with a projecting pin, and said elongated conductive member comprises a block extending across said pins and supported by a flexible strip.

6. A pole-type single-cavity magnetron comprising a cavity resonator containing a plurality of spaced parallel elongated anode poles extending across said resonator, and means for modulating the resonant frequency of said resonator, 70 by varying the capacitance between said poles, comprising an elongated conductive member movably mounted in said resonator adjacent at least two of said poles intermediate the ends thereof and means for vibrating said member toward and away from said poles.

7. A pole-type magnetron including a single cavity resonator containing at least two parallel elongated anode poles, and means for modulating the generated frequency of said cavity resonator, by varying the capacitance between said poles, comprising an elongated conductive member movably mounted adjacent and across said poles and means for vibrating said member toward and away from said poles, said vibrating means including means for establishing a constant magnetic field substantially normal to said member and means connecting said member in series with a source of modulating current.

8. A magnetron including an elongated cathode, a plurality of anode elements adjacent and parallel to said cathode, means for establishing a constant magnetic field substantially parallel to said cathode and said anode elements, and means for varying the operating frequency of said magnetron, by varying the capacitance between said anode elements, comprising an elongated conductive member movably mounted near two ad-

10 jacent anode elements and lying in a plane extending transversely of said anode elements, and means connecting said conductive member in series with a source of modulating current, whereby said member is vibrated toward and away from said two anode elements when said magnetic field is established and a modulating current is passed through said conductive member during operation of said magnetron.
